CLAIM

The ornamental design for a holder for an electric shaver, as shown and described.

DESCRIPTION

FIG. 1 is a perspective view of a holder for an electric shaver;

FIG. 2 is a perspective view of a holder for an electric shaver of FIG. 1;

FIG. 3 is a front view of a holder for an electric shaver of FIG. 1;

FIG. 4 is a rear view of a holder for an electric shaver of FIG. 1;

FIG. 5 is a right side view of a holder for an electric shaver of FIG. 1;

FIG. 6 is a left side view of a holder for an electric shaver of FIG. 1;

FIG. 7 is a top view of a holder for an electric shaver of FIG. 1; and,

FIG. 8 is a bottom view of a holder for an electric shaver of FIG. 1.

The broken lines in the figures represent structure and boundaries that are not part of the claimed design of the holder for an electric shaver, but rather show the environment in which the design is associated.
